W. H. BRADT.
ELECTRIC ALARM FOR PRESSURE GAGES.

No. 514,697.

Patented Feb. 13, 1894

UNITED STATES PATENT OFFICE.

WILLIAM H. BRADT, OF TROY, NEW YORK.

ELECTRIC ALARM FOR PRESSURE-GAGES.

SPECIFICATION forming part of Letters Patent No. 514,697, dated February 13, 1894.

Application filed November 22, 1893. Serial No. 491,612. (No model.)

To all whom it may concern:

Be it known that I, WILLIAM H. BRADT, a citizen of the United States, residing at Troy, county of Rensselaer, and State of New York, 5 have invented certain new and useful Improvements in Electric Alarms for Pressure-Gages, of which the following is a specification.

My invention relates to such improvements 10 and consists of the novel construction and combination of parts hereinafter described and subsequently claimed.

Reference may be had to the accompanying drawings, and the letters of reference marked 15 thereon, which form a part of this specification.

Similar letters refer to similar parts in the several figures therein.

The object of my invention is to provide an 20 electrical alarm-signal for gages that can be attached to well known forms of gage with little expense; and to provide for easily and quickly testing the apparatus by causing a contact of the circuit-closing electrodes by 25 means of mechanism without the case of the gage.

Figure 1 of the drawings is a plan view of 30 the face of a common form of pressure-gage provided with my improvements a portion of the case and dial being broken away to show the testing apparatus. Fig. 2 is a cross-section of the same taken on the broken line 2—2, in Fig. 1. Fig. 3 is a view in elevation of the testing-finger removed.

35 Referring to the drawings, A— represents a well known form of pressure-gage having an index A'— operated by a Bourdon-tube A²— and intermediate links in the usual manner, a portion of the tube and one of the 40 links A³— being shown in Fig. 1.

B— is an electric battery which may be of any known form; and C— is an electro-magnetic signal bell located in the battery circuit. A line wire B'— connects one pole of 45 the battery with the gage-case at B²—, and, with the case and index-pinion A⁴— forms a continuous connection between the battery and the index, the index forming the movable electrode of the circuit-closing mechanism. The other electrode is formed by the

contact-hand D— insulated from the index and having its end offset to form a contact-finger D'— in the path of the index. The contact-hand is pivoted concentrically with the index, upon a sleeve D²— inserted in the 55 central aperture in the dial D³— surrounding the index-pinion. The sleeve is provided on its lower or inner end with a shoulder D⁴— abutting on the under side of the dial, and its upper or outer end is screw-threaded to receive and fit the similarly threaded clamping-nut D⁵— by means of which the contact-hand is securely clamped to the dial. The dial, 60 with its contact-hand secured thereto, is insulated from the case of the gage and the index in electrical connection therewith, by means of the washers D⁶— of rubber or other insulating material between which the dial is clamped by the screws S— which secure 65 the dial to the case. 70

As shown in Fig. 2, the screw S— passes through both washers and the interposed dial, the screw-aperture in the dial being sufficiently large to prevent contact of the screw 75 with the dial.

A binding-post E— is secured in an aperture in the case wall by the nut E'— on its inner threaded end, the post and nut being insulated from the case by the insulating sleeve E²— and washer E³—. The inner end 80 of the post is connected by the conductor E⁴— with the dial, and the outer end by the line-wire B²— with the remaining pole of the battery, whereby the contact-hand D— is connected through the dial and intervening conductors with such pole of the battery, and forms the fixed electrode of the circuit-closing mechanism. When the gage-pressure has caused the index-operating mechanism to move the index into engagement with the contact-hand, the circuit will be closed by the contact of the electrodes, and the alarm signal will be rung. By loosening the clamping-nut D⁵— the contact-hand may be oscillated on the sleeve D²— to assume any radial 85 position on the dial, and may be locked in such position by the clamping-nut. By thus varying the position of the contact-hand, the alarm will be given when the pressure reaches 90 any predetermined degree. By employing 95 100

two of such contact-hands arranged with their contact-fingers on opposite sides of the index, I can combine in the same gage both high-pressure and low-pressure alarms.

5 Electrical pressure-alarms as heretofore constructed have been regarded with distrust and suspicion by many, on account of their uncertainty of operation at critical times. This is frequently caused by the failure of 10 the battery-current; and quite as often, perhaps, by the electrodes becoming corroded or coated with oil, dust or other matter, which prevents the contact of the electrodes. The latter is frequently the case when the gage- 15 pressure reaches its alarm-limit at infrequent intervals.

I have shown in the drawings a device which can be easily applied to an alarm-gage, by means of which the electrodes can be brought 20 into contact at frequent intervals to close the circuit for testing the battery, and remove and prevent any accumulation of dust or other substance upon the electrodes.

A finger F— is loosely inserted in an aperture in the case-wall of the gage, and secured 25 therein by the shoulder or flange F'— on the finger which bears upon the outer side of the wall, and the pin F²— passed through an aperture in the finger on the inner side of the case, as shown in the sectional portion of Fig. 30 1. The inner end of the finger projects interiorly of the case transversely of the end of the Bourdon-tube; and the outer end of the finger is provided with an operating handle F³— projecting exteriorly of the case. The finger fitting loosely in the case-wall aperture, may be oscillated by means of its handle 35 F³— to act as a lever and force its inner end against the Bourdon-tube, moving the tube 40 and other index-operating mechanism of the gage; and producing the same results upon such mechanism and the index as when the tube is subjected to internal pressure. A sufficient movement of the finger will thus cause 45 the index to indicate the alarm degree of pressure and thereby cause a contact of the electrodes, whereupon the alarm will be sounded if the apparatus is in working order. The handle F³— being accessible from without the 50 gage-case, the testing operation can be repeated very frequently without inconvenience. Besides testing the battery-current, the frequent contact of the electrodes tends

to prevent accumulations of dust and other substances thereon, keeping their contact surfaces clean and in an operative condition.

The form of the testing-finger may be varied as desired to adapt it to different constructions of gage, it only being necessary for the finger to be engageable with the index-operating mechanism within the gage-case and accessible from without such case.

What I claim as new, and desire to secure by Letters Patent, is—

1. In a circuit-closing device for gages, the 65 combination with the gage-case and dial insulated therefrom, of the gage-index in electrical connection with the case; a contact-hand pivoted concentrically with the index in electrical connection with the dial and offset 70 into the path of the index; a clamp for locking the contact-hand in adjusted positions, and means for connecting the case and dial with the respective poles of an electric battery having an electro-magnetic alarm-signal 75 in circuit, substantially as described.

2. The combination with an electric battery having an electro-magnetic alarm-signal in circuit, of a pressure-gage having its index electrically connected with one pole of the 80 battery, a sleeve inserted in the central aperture in the dial of the gage, having one end screw-threaded and having a shoulder on the other end abutting on the dial; a contact-hand pivoted upon the sleeve and insulated from 85 the index; a finger on the contact-hand projecting into the path of the index; an electrical connection between the other pole of the battery and the contact-hand; and a clamping-nut upon the threaded end of the sleeve, 90 substantially as described.

3. The combination with a gage having electrodes arranged to be brought into contact by the movement of the index-operating mechanism, of a lever fulcrumed upon the case- 95 wall of the gage, and engageable with the index-operating mechanism interiorly of the case, and an operating handle on the lever projecting exteriorly of the case, substantially as described.

In testimony whereof I have hereunto set my hand this 18th day of November, 1893.

WM. H. BRADT.
